EDWIN S. EBERLEIN, OF PITTSBURGH, PENNSYLVANIA, ASSIGNOR OF ONE-HALF TO
WALTER J. CLAPPER, OF PITTSBURGH, PENNSYLVANIA

STAIR FOR RAILROAD COACHES AND THE LIKE

Application filed April 6, 1931. Serial No. 527,948.

This invention relates to improvements in stairs and more in particular to stairs used on vehicles, such as railway-coaches, electric cars, automobile busses, and so forth.

Referring especially to the application of this invention to railroad coaches, it may be said that in the modern coaches the lower-most steps of their stairs are generally placed a considerable height above the railroad platform, and that in order to enable passengers to comfortably climb or descend these steps it is necessary to place on the platform a portable foot-stool which acts as an additional step. Aside of the trouble and delay occasioned by the use of this stool, accidents are liable to occur because of the instability of said stool which may be easily tipped over by the passengers, especially so when the site upon which it is placed is not perfectly level or even.

One of the primary objects of this invention is to provide such stairs having at their lower ends an additional step which may be placed into operative position from within the railroad coach. Another object of this invention is to provide a system of levers for operating the additional step which is automatically locked in its operative or inoperative position and which can only be actuated after precautionary acts for the safety of train passengers have been performed. Still another object of this invention is to provide an additional step to ordinary stairs which is applicable, upon making relatively simple alterations, to old stairs as well as to new ones.

Additional features and advantages of this invention will appear in the following description considered in connection with the accompanying drawings forming a part of this application, and in which:

Fig. 1 is a front elevation of railroad stairs showing one embodiment of this invention.

Fig. 2 represents a cross-sectional view taken on line 2—2 in Fig. 1.

Fig. 3 is a cross-sectional view taken on line 3—3 in Fig. 2.

Fig. 4 is a side-elevation of a combined guide and locking means for the operating lever used in the above embodiment.

Fig. 5 is a top-plan view of Fig. 4.

Fig. 6 is a front elevation of one of the levers used in Figs. 1 and 2.

Fig. 7 is a front elevation showing a modified construction of this invention.

Fig. 8 represents a cross-sectional view taken on line 8—8 in Fig. 7.

Fig. 9 shows a front elevation of still another modification of the invention.

Fig. 10 is a cross-section along line 10—10, Fig. 9.

Fig. 11 is a cross-sectional view taken substantially on line 11, in Fig. 9.

Fig. 12 is a fragmentary plan view of the end of a railroad coach provided with stairs of my invention.

Fig. 13 is a fragmentary side-elevation of the railroad coach and stairs shown in Fig. 12.

Reference being had to Figs. 1 to 6, the railroad coach stairs shown therein comprise the stationary steps 1 the lowermost of which, (in modern coaches), does not protrude beyond the contour of the coach. To prevent accidents to passengers and employees these coaches are also provided with side-doors 2 and with trap-doors 3 to cover the wells of said stairs. These doors are generally closed during the running of the train for the protection of human beings and to reduce air-drafts and dust within the coach.

The auxiliary step 4, at the lower end of the permanent steps 1, is of the sliding type and comprises a tread board 5 mounted on top of a frame consisting of the front board 6 and the two side boards 7 which are considerably longer than the tread of said extra-step to provide sufficient support to the latter when in extended position.

Mounted within the side-boards are the outwardly open channels 8, closed at both ends,

which act as run-ways for the rollers 9 rotatably mounted on stationary pins 10 secured in any desired manner to the stair-stringers 11.

5 This auxiliary step is actuated back and forth by means of an operating lever 12 secured at one end of a cross-shaft 13 mounted rotatably in bearings 14 mounted conveniently on the underside of the stairs. Fastened 10 to this shaft are two lever-arms 15, each having at its lower end an elongated slot 16 engaged by an inwardly directed pin 17 secured adjacent the free end of each side board 7.

The operating-lever 12 is guided and limited 15 in its movement by a guide member 18 comprising two arcuate and parallel side members 19 and 20 held in spaced relation to slidingly receive therebetween the operating-lever by means of spacer-blocks 21 of 20 slightly greater height than the thickness of the operating lever, the whole being tied together in any desired manner, such as by bolts 22 by means of which the guide-member may also be secured at one side of the stairs.

25 In one of the side-members, say in 20, there are cut recesses 23 and 24 in which the operating-lever may partly nest itself. These recesses are spaced to correspond to the two extreme positions of the operating-lever. 30 This lever is slightly bent laterally in the direction of the recesses, so that it will engage same due to its inherent resiliency, and can only be disengaged by exerting a transverse pull away from the recess.

35 As shown in Fig. 2, the operating-lever is so mounted on the cross-shaft that when the auxiliary step is extended in operative position, it will be in a nearly vertical position in front of the raised trap door 3 and will 40 thus preclude the dropping of the latter over the stair-well unless the operating-lever has been pushed forward below the floor level of the coach to retract this auxiliary step, as indicated in dot and dash lines.

45 As is well known, for safety reasons all the trap-doors and outside doors of modern coaches must be closed before the train is started. By virtue of the above described arrangement of the operating-lever in relation 50 to the trap door, the full retraction of the auxiliary step within the outline of the coach is automatically assured and accidents due to collision with said step are prevented.

Suitably located in the floor of the vestibule 55 25 of the railroad coach is a slot 26 (Fig. 12) of ample width and length to accommodate the movement of the operating-lever 12 and to enable access thereto when in its lowered position, corresponding to the inoperative 60 position of the auxiliary step.

In the embodiment shown in Figs. 7 and 8 the auxiliary step 27 is hinged to the stationary part of the stairs. This step comprises the rigidly connected tread 28 and the 65 riser 29. The latter is here shown hingedly

connected to the underside of the lowermost step 1 by means of hinges 30.

The counter clock rotation of the auxiliary lever into the inoperative position shown in dot and dash lines in Fig. 8 is again effected by means of an operating-lever of similar shape and mounting as herein-above described and therefore identified by the same reference-numerals.

70 Upon the cross-shaft 13 are securely mounted in any desired manner the two lever-arms 31 to which are hingedly connected by means of a pin-connection 32 the upper ends of the connecting-links 33 the lower ends of which are hinged by the pin connections 34 to cleats 35 secured at both ends and underneath the auxiliary tread board 28.

75 As will be readily seen from Fig. 8, a counterclock rotation of the operating-lever 12 into the lowermost position shown in dot and dash lines will cause the retraction of the auxiliary step and enable the closing of the side-door 2 and the trap-door 3 over the stair-well. This operating lever is again guided and locked in either one of its extreme positions by means of a guide-member 18 above described and detailed in Figs. 4 and 5.

80 The auxiliary step 36 shown in Figs. 9 to 11 is also of the hinged type. It comprises a tread 37 and a riser 38 rigidly connected thereto by screws and by the two bell-crank levers 39. The latter are secured to a cross-rod 40 rotatably mounted in suitable bushings 41 secured in the stair-stringers 11. In the rear-arm 42 of each lever 39 there is an elongated slot 43 to which is slidably connected by a pin-connection 44 the bifurcated lower end 45 of a suitably curved lever-arm 46 mounted securely on the cross-shaft 13, which may be actuated by means of the operating-lever 12. This lever is also guided and locked by guide-means, as shown in Figs. 4 and 5, and its disposition relative to the side-door and the trap-door is as aforementioned.

85 A downward push of the operating lever into the dot and dash position shown in Fig. 10 will cause a clockwise rotation of the auxiliary step into inoperative position.

To relieve the lever mechanism of any strains when the auxiliary step is in operative position, stops 47 are fastened on the inside of the stringers 11 against which stops the riser 38 bears. As shown in Figs. 9 and 11, the tread-board 37 of the auxiliary step 115 is made shorter than its riser to clear these stops and allow said step to assume its inoperative position.

90 As will be understood, as suggested herein, there may be slight changes made in the construction and arrangement of the details of my invention without departing from the field and scope of the same, and I intend to include all such variations, as fall within the scope of the appended claims, in this application.

cation in which the preferred forms only of my invention are disclosed.

I claim:

1. In a railway coach and the like, the
5 combination of a stair having stationary
steps and stringers, an auxiliary horizontal-
ly movable step positioned at the lower end
of said stair; means positioned on said string-
ers for slidably supporting said auxiliary
10 step in a fixed horizontal plane; a lever oper-
able from within said coach to actuate said
auxiliary step in and out of operative posi-
tion; unitary means positioned on one of
the stringers to guide and limit the move-
15 ment of said lever; said guide-means having
recesses adapted to be engaged by the lever,
and said lever being transversely resilient
and initially bent in the direction of said
recesses to normally engage same.

coach; said lever being so disposed that a portion thereof will be in front of said side-door and trap-door when in open position whereby said auxiliary step must be placed in inoperative position to enable the closing of said doors; unitary means positioned on one of the stringers to guide and limit the movements of said lever; said guide means having recesses adapted to be engaged by the lever and said lever being transversely resilient and initially bent in the direction of said recesses to normally engage same.

In testimony whereof I affix my signature.

EDWIN S. EBERLEIN.

20 2. In a railroad coach and the like having a stair comprising stationary steps and stringers, a side-door and a trap-door adapted to close the stair-well, the combination of an auxiliary horizontally movable step positioned at the lower end of said stair; means positioned on said stringers for slidably supporting said auxiliary step in a fixed horizontal plane; a manually operable lever to actuate said auxiliary step from within the
25 coach; said lever being so arranged that the auxiliary step must be placed in inoperative position to enable the closing of said doors; unitary means positioned on one of the stringers to guide and limit the movements
30 of said lever; said guide-means having recesses adapted to be engaged by the lever and said lever being transversely resilient and initially bent in the direction of said recesses to normally engage same.

35

40 3. In a railroad coach and the like having
a stair comprising stationary steps and
stringers, a side-door and a trap-door adapt-
ed to close the stair-well, the combination of
an auxiliary horizontally movable step po-
45 sitioned at the lower end of said stair; means
positioned on said stringers for slidably sup-
porting said auxiliary step in a fixed hori-
zontal plane; a manually operable lever to
actuate said auxiliary step from within the
50 coach; said lever being disposed so that a
portion thereof will be in front of said side-
door and trap-door when in open position,
whereby said auxiliary step must be placed
55 in inoperative position to enable the closing
of said doors.

4. In a railroad coach and the like having a stair comprising stationary steps and stringers, a side-door and a trap-door adapted to close the stair-well, the combination of an auxiliary horizontally movable step positioned at the lower end of said stair; means positioned on said stringers for slidably supporting said auxiliary step in a fixed horizontal plane; a manually operable lever to actuate said auxiliary step from within the

26 tioned at the lower end of said stair; means positioned on said stringers for slidably supporting said auxiliary step in a fixed horizontal plane; a manually operable lever to actuate said auxiliary step from within the
30 coach; said lever being so arranged that the auxiliary step must be placed in inoperative position to enable the closing of said doors; unitary means positioned on one of the stringers to guide and limit the movements
35 of said lever; said guide-means having recesses adapted to be engaged by the lever and said lever being transversely resilient and initially bent in the direction of said recesses to normally engage same.

40 3. In a railroad coach and the like having
a stair comprising stationary steps and
stringers, a side-door and a trap-door adapt-
ed to close the stair-well, the combination of
an auxiliary horizontally movable step po-
45 sitioned at the lower end of said stair; means
positioned on said stringers for slidably sup-
porting said auxiliary step in a fixed hori-
zontal plane; a manually operable lever to
actuate said auxiliary step from within the
50 coach; said lever being disposed so that a
portion thereof will be in front of said side-
door and trap-door when in open position,
whereby said auxiliary step must be placed
55 in inoperative position to enable the closing
of said doors.

4. In a railroad coach and the like having a stair comprising stationary steps and stringers, a side-door and a trap-door adapted to close the stair-well, the combination of an auxiliary horizontally movable step positioned at the lower end of said stair; means positioned on said stringers for slidably supporting said auxiliary step in a fixed horizontal plane; a manually operable lever to actuate said auxiliary step from within the

35 coach; said lever being so arranged that the auxiliary step must be placed in inoperative position to enable the closing of said doors; unitary means positioned on one of the stringers to guide and limit the movements of said lever; said guide-means having recesses adapted to be engaged by the lever and said lever being transversely resilient and initially bent in the direction of said recesses to normally engage same.

40 3. In a railroad coach and the like having
a stair comprising stationary steps and
stringers, a side-door and a trap-door adapt-
ed to close the stair-well, the combination of
an auxiliary horizontally movable step po-
45 sitioned at the lower end of said stair; means
positioned on said stringers for slidably sup-
porting said auxiliary step in a fixed hori-
zontal plane; a manually operable lever to
actuate said auxiliary step from within the
50 coach; said lever being disposed so that a
portion thereof will be in front of said side-
door and trap-door when in open position,
whereby said auxiliary step must be placed
55 in inoperative position to enable the closing
of said doors.

4. In a railroad coach and the like having a stair comprising stationary steps and stringers, a side-door and a trap-door adapted to close the stair-well, the combination of an auxiliary horizontally movable step positioned at the lower end of said stair; means positioned on said stringers for slidably supporting said auxiliary step in a fixed horizontal plane; a manually operable lever to actuate said auxiliary step from within the
